AUTOMATIC SWITCH-OVER SIGNAL
FOR TELEPHONES

Frank A. Leibe, Quakertown, Pa., and Walter A. Miner, Jr., New York, N. Y., assignors to Federal Telephone and Radio Corporation, New York, N. Y., a corporation of Delaware

Application May 1, 1943, Serial No. 485,314

15 Claims. (Cl. 179—81)

This invention relates to telephone systems of the type in which a receiver and a transmitter at one end of a telephone line are alternately switched into operation, an arrangement especially suitable for field telephones. In systems of this type it is desirable to provide signaling means for indicating the end of transmission and the switching of the set from transmitting to receiving position so that the other operator will be advised that he can commence transmission. The invention is particularly adapted for use in systems employing vacuum tube amplifiers at each end of the line.

The general object of the invention is to provide a novel switch-over signal of the indicated type, and specifically a signal that may be used with arrangements in which the amplifier as a whole can be connected either to the transmitter or to the receiver.

A feature of the invention includes an arrangement employing a positive feedback circuit in the amplifier arranged for connection during a brief signal period to generate signal-producing oscillations in the amplifier circuits. A specific purpose is the provision of automatic means for connecting and disconnecting such feedback circuit, operative when the set is switched from transmitting to receiving position. A further feature comprises the use for this purpose of a switching arrangement including an automatic timing device such as a time delay unit or a circuit having a predetermined time constant which regulates the duration of the signal. Another feature is the utilization of a unitary switching arrangement for controlling both the transfer of the set connections between transmitting and receiving positions and the actuation of the feedback circuit during a signaling period.

Other objects and advantages will appear from the following description considered in connection with the accompanying drawing, in which a circuit embodying the invention is diagrammatically illustrated.

The disclosed embodiment comprises a conventional transmitting and receiving handset 10 including a receiver 11 connected by lines 12 and 13 across a section of an induction coil 14, with the usual blocking condenser 15 in line 12, and a transmitter microphone 16 connected by lines 13 and 17 across another section of coil 14, with a push-to-talk switch 18, battery 19, relay 43 and bypass condenser 20 in line 17.

The handset 10 is coupled to a vacuum tube amplifying system 23 by switch means 24 arranged to connect the amplifying system between

the handset 10 and line 25 either in receiving position with the amplifying system input connected to the line and its output to the handset, or in transmitting position with these connections reversed. The amplifying system 23 may include any desired number of tubes; and while two tubes are illustrated, the arrangements disclosed are applicable to amplifying systems having either a smaller or a larger number of tubes.

10 The handset 10 is coupled to the amplifying system 23 through a transformer 26 having a coil 27 connected across induction coil 14 and condenser 15, and inductively associated coils 28 and 29 connected to the output and input respectively 15 of the amplifying system 23 through switch means 24. Line 25 is connected to the amplifying system through transformer 30 having coil 31 connected across the line and coils 32 and 33 connected to the input and output respectively of 20 the amplifying system through said switch means. Coil 29 of transformer 26 is connected at one end to ground and at the other end to contact 35 of double throw switch 36, which is connected to the input of the amplifying system 25 23, the output of which is connected through contact 37 of double throw switch 38 and line 39 to one end of coil 28, the other end being connected to a source of positive potential providing 30 amplifier tube anode current. Coil 32 of transformer 30 is connected at one end to ground and at the other end to contact 40 of switch 36, contact 41 of switch 38 being connected to coil 33 35 of transformer 30, the other end of which is connected to a source of positive anode potential.

35 It will be apparent that with this arrangement the simultaneous operation of switches 18, 36 and 38 will switch the handset 10 and amplifying system 23 between receiving and transmitting positions. A suitable arrangement for simultaneous

40 operation of these switches is provided, the form illustrated employing a relay arrangement. The latter includes a primary relay 43 connected across condenser 20 and energized by battery 19 when switch 18 is closed. A normally open switch 44 actuated by relay 43 is in circuit between the grounded winding 45 of secondary relay 46 and resistance 48 connected to a suitable grounded 45 source of positive potential for energizing relay 46. The latter relay operates switches 36 and 38, 50 which are normally held in receiving position indicated in full lines, but are shifted to transmitting position, indicated by dotted lines, when relay 46 is energized by the closing of switch 44 due to the energizing of relay 43 through the closing of switch 18. The portion of switch means 24

thus far described will therefore operate to switch the amplifying system 23 automatically between receiving and transmitting positions when the handset 10 is similarly shifted by switch 18.

In the particular amplifying system illustrated, employing two vacuum tubes 50 and 51, switch 36 is connected to control grid 52 of tube 50, said grid and cathode 53 being appropriately connected to provide the necessary potentials. Cathode 53 is connected through grid bias resistance 56 to ground, and anode 57 is connected through a suitable resistance 58 to a source of positive potential.

The output circuit of tube 50 is suitably coupled to the input circuit of tube 51. In the illustrated arrangement anode 27 is connected through coupling condenser 61 to control grid 62 of tube 51 and the usual resistor 63 to ground. Cathode 65 is connected through the usual grid bias resistor 66 and bypass condenser 67 to ground. Anode 68 is connected through line 69 to switch 38.

A negative feedback arrangement may be provided to improve the operation of the amplifying system 23, the illustrated embodiment utilizing for transmitting a circuit through line 70, including condenser 71 and resistance 72, connecting contact 41 of switch 38 with cathode 53 of tube 50, and for receiving, a circuit from line 39 through line 73, including condenser 74a and resistance 74b, to an adjustable connection to resistance 56 which provides a gain control.

The signaling means is arranged to couple the output and input circuits of amplifying system 23 so as to produce oscillations when the handset 10 is switched to receiving position, such oscillations when sent out over line 25 being appropriate to produce an audible signal in the receiver at the other end of the line. An arrangement is also advantageously included for terminating such coupling after a predetermined period and thereby limit the signal length. An automatic construction for this purpose is disclosed.

In the illustrated construction a signal circuit 75 is introduced by switch means into amplifying system 23 when switch 18 is closed, and is automatically disconnected after a relatively brief signal period. The form shown employs a feedback circuit connecting anode 68 of tube 51 and the control grid-cathode circuit of tube 50. It includes a connection to line 69 through contact 76 of switch 77, and extends through condenser 78 and resistance 79 in line 89, to line 39, which is connected to winding 28 of transformer 26, inductively coupled to winding 29 connected through contact 35 of switch 36 to grid 52 of tube 50. Switch 77 is normally closed and is opened by relay 43 when the latter is energized. It therefore remains open during transmission but is closed when push-to-talk switch 18 is opened.

Means is provided for holding switches 36 and 38 in transmitting position during a brief signal period following the opening of switch 18 and the closing of feedback switch 77, so that the feedback circuit 75 may operate to produce the signal oscillations. For this purpose a suitable arrangement is employed for keeping secondary relay 46 in operation after the opening of the circuit of primary relay 43 has resulted in the opening of switch 44. While this may be accomplished in different ways, such as the use of a relay having mechanical means for delaying switch action, or a time delay circuit employing a vacuum tube, a simple arrangement is disclosed, comprising a condenser 81 shunted across winding 45 of relay

46 and having the characteristics necessary to maintain on said winding a sufficiently high potential to keep switches 36 and 38 in inner or transmitting position during a signal period the duration of which is determined by the ratio at which the charge on condenser 81 leaks off. The signal duration may therefore be regulated by the selection of a suitable condenser.

While a preferred embodiment has been illustrated and described, the particular arrangement disclosed has been set forth for purposes of exemplification of the invention and not by way of limitation, since it may be modified without departing from the invention, the scope of which is indicated by the claims.

What is claimed is:

1. A telephone transmitting and receiving unit including a transmitting circuit, a receiving circuit, a vacuum tube amplifying system associated with the transmitting circuit, switch means for placing said circuits alternately in operation, means including a feedback signal circuit arranged for connection to the amplifying system to produce signaling oscillations of a singing character and ephemeral duration therein, and signal control means including a time delay circuit for placing said signal circuit means out of operation after a predetermined period of time.

2. A telephone unit as set forth in claim 1, including switch means for changing the connections between the amplifying system and the transmitting and receiving circuits, said switch means actuating the signal control means.

3. A telephone unit as set forth in claim 1, in which said signal circuit is arranged to provide oscillation-producing feedback between the output and the input of the amplifying system.

4. A telephone unit as set forth in claim 1, in which the amplifying system includes negative feedback when talking and the signal circuit includes means for producing positive feedback in the amplifying system for a predetermined period of time only.

5. A telephone transmitting and receiving unit including a transmitting circuit, a receiving circuit, a vacuum tube amplifying system, switch means for coupling the amplifying system alternately to the transmitting and receiving circuits, a signal circuit arranged for connection to the amplifying system to produce regenerative signaling oscillations therein, and signal control circuit means including a relay for placing said signal circuit out of operation after a predetermined period of time.

6. A telephone unit as set forth in claim 1, in which the switch means includes an operating switch and intermediate switch means controlled thereby arranged to connect the amplifying system alternately to the transmitting and receiving circuits, switch means actuated by the control switch for connecting the signal circuit to the amplifying system when the control switch is shifted from transmitting to receiving position, and time delay circuit means for maintaining said intermediate switch means in transmitting position during a signal period following said actuation of the operating switch.

7. A telephone transmitting and receiving unit including a transmitting circuit, a receiving circuit, a vacuum tube amplifying system, switch means for coupling the amplifying system alternately to the transmitting and receiving circuits including a connection changing switch construction, a relay controlling said switch construction and a master switch controlling the relay, a feed-

back signal circuit arranged for connection to the amplifying system to produce signaling oscillations of singing type and having a predetermined duration therein, and signal control means for placing said signal circuit in and out of operation including a control switch connecting the signal circuit to the amplifying system, means controlled by the master switch for actuating the control switch arranged to close the control switch when the master switch is shifted to receiving position, and time delay circuit means for holding the relay-controlled switch construction in transmitting position during a signal period after the master switch is shifted to receiving position.

8. A telephone unit as set forth in claim 7, in which the switch holding means comprises means for maintaining an energizing potential on the relay for a predetermined period after the master switch is shifted to receiving position.

9. A telephone unit as set forth in claim 7, including relay means controlled by the master switch for actuating said relay and the signal circuit control switch.

10. A telephone unit according to claim 5, including connections extending so that the switch for changing the connections between said amplifying system and said transmitting and receiving circuits, respectively, also controls a relay which in turn actuates the signal control device.

11. A telephone unit according to claim 5, also including connections extending so that the circuit of the signal producing device is arranged to provide oscillation-producing feedbacks between the output and the input sections of said amplifying system.

12. A telephone unit according to claim 5, also including connections extending so that the amplifying system includes means for yielding negative feedbacks, the signal circuit includes connections for producing positive feedback in said amplifying system, and the positive feedback is sufficiently great to overcome the effect of said negative feedback, so that the system will oscillate only

when said positive feedback is connected into the circuit.

13. A telephone transmitting and receiving unit according to claim 5, also including two relays and connections extending so that said switch is arranged to couple said amplifying system alternately to the transmitting and receiving circuits, said signal producing circuit is arranged for connection to the amplifying system for only a brief interval, at the time of change-over, so as to produce signaling oscillations therein, and said signal control device for placing said signal producing circuit in and out of operation, actuates the first of said relays, which latter in turn actuates a second relay, said second relay having slow release action.

14. A telephone unit according to claim 5, in which the switch as a whole includes an operating switch and an intermediate switch controlled thereby, and is arranged to connect said amplifying system alternately to the transmitting and receiving circuits, so that said switch as a whole is actuated by operation of the control switch so as to connect the signal producing circuit to the amplifying system when the change-over control switch is shifted from transmitting to receiving position, and also including a slow release relay which maintains said intermediate switch in transmitting position during a signal transmission period following the actuation of said operating switch.

15. A telephone unit according to claim 5, including a slow release relay and in which the switch holding arrangement comprises a capacitive device in parallel to the relay winding for maintaining an energizing potential on said slow release relay for a predetermined period after the change-over switch is shifted to receiving position so as to delay the restoration thereof to inoperative position, after actuating current is removed from said relay.
